ELECTRODE MOUNTING FOR ELECTRON
DISCHARGE DEVICES

John J. Borzin, Newark, and William G. Moran,
Bloomfield, N. J., assignors to Westinghouse
Electric Corporation, East Pittsburgh, Pa., a
corporation of Pennsylvania

Application June 14, 1945, Serial No. 599,412

2 Claims. (Cl. 250—27.5)

1

This invention relates to electron discharge devices and more particularly to such as are intended for and capable of handling large amounts of power.

In devices of the general character indicated above, it is a common practice to provide support and lead-in connections at opposite ends of the tube. Mechanical difficulty is experienced with such tubes in obtaining and maintaining coaxial alignment of the several electrodes and at the same time to have a structure capable of convenient fabrication and rapid but accurate assemblage.

Accordingly, an object of the present invention is to obtain an electron discharge device with opposed stems which is readily assembled.

Another object of the invention is to obtain axial alignment and rigidity of electrodes capable of such ready assembly.

Other objects of the invention will appear to those skilled in the art to which it appertains both by direct recitation thereof as the description proceeds and by implication from the context.

Referring to the accompanying drawing in which like numerals of reference indicate similar parts throughout the several views:

Figure 1 is a sectional elevation of an electron discharge device embodying the invention;

Figure 2 is a similar sectional elevation of the electrode structure and stems somewhat enlarged over Fig. 1 and at right angles to the showing of and on line II—II of Fig. 1;

Figure 3 is a cross-sectional view on line III—III of Fig. 1; and

Figure 4 is an enlarged sectional elevation of the end portion of the electrodes and support therefor shown at the bottom part of Fig. 1.

In the specific embodiment of the invention illustrated in said drawing, the electron discharge device there shown provides a spiral or coiled filamentary cathode 10 through which extends an axially positioned support rod 11. Outside of the cathode coil and coaxial therewith is a helical control grid 12, and, if desired, another but larger coaxial helical screen grid 13 may be provided. All these parts, namely the said cathode, its rod 11 and the two grids are supported from and have lead-in connection through one or the other or both of opposite end stems 14, 15 formed as part of the glass 16.

A coaxial anode 17 is provided around a mid portion of the screen grid, this anode being shown as supported by and having lead-in connection through a stem 18 at the side of and formed as

2

part of the said envelope. Other means of support for the anode, well known in the prior art, however, may be substituted.

Just as a matter of convenience, the description will refer to parts in their positions as appearing in the drawing, although it will be understood that the posture of the device is wholly arbitrary and might just as well have been with the other end up, horizontally or otherwise.

10 The particular cathode shown herein is a coiled wire filament the lead-in wires for which, according to the arbitrary location of parts mentioned above, are sealed through the upper stem 15, one of the filament lead-in wires being the 15 aforementioned axially positioned support rod 11. This rod extends through the middle of the upper stem and longitudinally through the cathode, terminating short of the opposite or bottom stem 14. The other or second lead-in wire 19 for 20 the filament is at one side of said rod 11 and, of course, insulated therefrom. Near the inner end of this second lead-in wire 19 is a ceramic or other spacer 20 through which the rod 11 likewise extends, said spacer being suitably held in 25 place and bracing the lead-in wires with respect to each other. Beyond the spacer 20 the filament is secured next the end of lead-in wire 19, said filament being spiral and around rod 11 but spaced therefrom to the far end of the filament 30 where the convolutions decrease in diameter so as to engage the end of the filament around the rod, as at 21, where it is welded or otherwise made secure but with the rod continuing therebeyond.

From the opposite stem 14, that is, the stem 35 shown at the bottom of the envelope in Fig. 1, and extending through said stem, are sealed two support rods 22 of which one or both may be for lead-in purposes. The inner ends of these support rods are welded or otherwise secured, as at 40 23, to corresponding two stay wires 24, of which there are four shown, and constituting part of control grid 12. By virtue of the use of several stays 24 longitudinally of the grid and welding of each convolution of the grid spiral winding to each stay, the grid is quite a rigid structure. The rods 22 by which the grid is supported are rigid and being rather widely separated afford good bracing for the grid to maintain its alignment even with rough treatment of the device. For 45 additional bracing, a spacer 25 is provided on the said rods 22 between the stem 14 and proximate or lower end of grid 12. This spacer is held by suitable means from movement longitudinally of the rods. Furthermore said spacer has a central hole therein through which aforementioned

central rod 11 may be slid during assembly and which therefore affords additional mutual bracing of the several rods from each other.

Screen grid 13 is shown as formed with a spiral winding around four stays 26 the length of which carries the end portions to situation juxtaposed to the sides of both stems 14, 15. Said stays are welded or otherwise secured to a clamp collar 27 at one end of the tube, the collar shown being around and tightened to grip stem 15. The other ends of the screen grid stays are yoked in pairs with resilient bands 28 that engage the side of stem 14 and thereby retain the screen grid substantially coaxial to the other electrodes and resist deflection of said grid even with rough usage.

It will be understood that the stems are separately fabricated and, with electrodes mounted therewith, finally assembled with the rest of envelope 16, evacuated and sealed. Central rod 11 and filament lead 19 are sealed in stem 15 and filament 10 is applied thereto while the stem is separate from the envelope. If screen grid 13 is to be incorporated in the device, it likewise is applied to stem 15 and clamped in axial alignment with the central rod and filament. A flexible connection 29 between one grid stay and a lead-in wire 30 is completed. After being properly positioned, the stem 15 is sealed to envelope 29.

Similarly, stem 14 is fabricated with the control grid leads therein and the control grid is applied on the said leads before the stem is incorporated in the device. The anode 17 is applied to its stem 18 and the stem sealed to the envelope. Then one of the other stems, for instance stem 15, is applied, inserting the screen grid, cathode and central rod through the anode. A side tap flexible lead 31 and external connector 32 may then be applied to afford external connection for the screen grid. Then the lower stem is applied by inserting the control grid axially into the screen grid and between the screen grid and cathode. As the stem approaches its final position, spacer 25 comes to the end of central rod 11 and caused to slide onto that rod until the control grid is at its proper longitudinal position. By virtue of the support from the spacer 25, it is a very simple matter to align the control grid, and this alignment is

effected by engagement of the resilient bands of the screen grid with the stem and may require only slight alteration of position by the operator. The stem is sealed to the envelope and the exhaust, seasoning, sealing and like operations then performed to complete the device as usual in the art.

We claim:

1. An electron discharge device comprising an envelope having stems at opposite ends thereof, a central rod projecting from one said stem, a cathode on said rod intermediate the ends thereof, mounting means protruding from the other stem and including the outer end of said rod therebetween, an electrode on said mounting means, and a spacer on said mounting means between the electrode thereon and the stem from which said mounting means protrudes, said spacer receiving and engaging a part of said rod included between said mounting means.

2. An electron discharge device comprising an envelope having stems at opposite ends thereof, a central rod projecting from one said stem, a cathode on said rod intermediate the ends thereof, mounting means protruding from the other stem and including the outer end of said rod therebetween, an electrode on said mounting means, and a spacer on said mounting means between the electrode thereon and the stem from which said mounting means protrudes, said spacer receiving and engaging a part of said rod included between said mounting means, and a third electrode having mounting means on one stem and having aligning means engaging the other stem.
